UNITED STATES PATENT OFFICE.

CLEVELAND G. TERRY, OF TUJUNGA, CALIFORNIA.

STOVE.

Application filed September 29, 1925. Serial No. 59,284.

My invention relates to a heating device and has particular reference to a stove using a gaseous fuel, the principal object of the invention being to provide a simple, economical and efficient stove in which the combustion gases passing out through the stack may be effectively used for increasing the circulation and displacement of air throughout and in a closed area.

Other objects of the invention are to provide a simple, compact and light heater in which the displacement of the air in a closed area is continuously taking place; in which no fumes or odors can escape to vitiate the air in a closed area; which will enable an area to be heated to uniform temperature, and to varying degrees of temperature, without cold or hot zones; to provide a heater which is entirely air insulated, and hence may with perfect safety be placed in walls; and to provide a heater by which pure fresh air may be delivered into and circulated about a room or other enclosure, and heated to a degree that will provide a comfortable atmosphere without impairing the vitality of the pure air by overheating and drying.

Other objects will appear from the following specification in connection with the accompanying drawing, which illustrates a preferred embodiment of the invention, and in which

Fig. 1 is a front view partly broken showing my invention.

Fig. 2 is a side view partly in section, the section taken approximately on line 2—2 Fig. 1, and

Fig. 3 is a sectional plan view on line 3—3 Fig. 1.

My invention is shown in one of many forms in which it may be carried into practical effect and as comprising in a general sense a structure having a communication with the atmosphere, for leading into a closed area the outside air, and another communication with the atmosphere for continuously carrying out the air from the closed area, with a means for heating the introduced atmospheric air.

In a more specific sense, the invention as shown in the preferred manner of construction, comprises a casing 1 formed with sides 2, back 3, and top 4 and which is open at the front and bottom. The sides 2, at the bottom thereof are formed into or provided with ducts or passageways 5, which

communicate in any desirable manner with the atmosphere outside an enclosed area or space. These ducts 5 extend the full depth of the sides 2 and are of limited height and width, and serve to convey the atmospheric air from the bottom into a room or other area, as will appear later. To the rear or back 3 of the casing and between the ducts 5, is fastened in any desirable manner, a partition 6, constituting a stack, extending vertically through said case 1 and at the bottom being in open communication with the closed area to be heated or ventilated, the partition 6, for this purpose terminating, a short distance from the bottom, and providing a free entrance of the used heated air into said stack.

The upper area of the stack 6 is enlarged, as seen at 6', and extends above the top of the casing 1, and to the wall 7 of said stack 75 enlargement are connected the elbows 8 of a plurality of spaced flues 9, the elbows 8 being, as seen, in communication with said stack. These elbows 8 are connected to the wall 7, at a short distance from the top 4 80 of the casing 1, the space A created by mounting the flues in this manner, serving to permit the incoming air to pass over the top of the flues. The flues 9, as seen, are also spaced from each other, from the side walls 2 and from the back 3 of the casing 1, and being thus entirely freely suspended within the casing, the incoming cold air readily and efficiently absorbs the heat of the flues on all sides and travels into the room in heated 90 condition, the temperature depending upon the heat in the combustion chamber 10. The flues 9 are conjoined with the combustion chamber 10, in which is disposed a burner 11, connected with a source of fuel supply, 95 not shown. The top of said combustion chamber is provided with openings 11' through which the heat of combustion escapes from the combustion chamber into the flues 9. These openings are considerably 100 smaller than the flue openings and are thus designed to retard the flow of the heat of combustion and thereby insure the fullest expansion of same within the flues. As shown, the combustion chamber 10 is carried or 105 supported by the flues 9, any suitable connection being used for this purpose, such for instance as that illustrated in Fig. 1, and comprising an upstanding collar 12 on the top of the combustion chamber to 110

which the flues 9 are fastened by bolts or other means. The construction of suspending the flues and the combustion chamber provides a cold air space entirely around 5 these parts and between them and the casing, and automatically insulates them from the casing. Therefore, regardless of the heat in the combustion chamber 10, the air space between the casing and flues, and between the flues efficiently insulates the casing 10 from the heat, which is absorbed by the cold air entering from the bottom. Special insulation, as covers, blocks or sheets of asbestos, or other fire proof materials are thus rendered 15 wholly unnecessary, and a heater of this type may safely be placed and concealed in the walls of a building.

Below the burner 11, in the combustion chamber 10, I prefer to place a baffle plate 20 12', which is suitably supported above the bottom 13 of the combustion chamber, and which serves to deflect the air entering the combustion chamber 10 through ports 14 in the bottom 13, around the burner, and thereby 25 prevent roaring, which would otherwise occur. Beneath the combustion chamber 10 I prefer to place a means for preventing the transfer of heat from the combustion chamber to the bottom and for confining the heat, 30 and directing also the incoming cold air about the combustion chamber. This means may be in the form of a plate 15, extending longitudinally of and under the combustion chamber 10, and supported upon the walls 35 of the ducts 5. The plate 15 is formed with an upstanding portion 15' extending in front of and for the full width of the combustion chamber 10, this upstanding portion co-operating with the plate 15 for the purposes described, and also for causing a part of the incoming cold air to be deflected and diverted 40 into the ports 14 in the bottom of the combustion chamber.

From the construction as outlined, it will 45 be observed that atmospheric air enters through the side ducts 5 and travels upwardly in the space B (Fig. 1), between the side walls 2, the combustion chamber 10 and the flues 9, and also behind the flues.

To prevent the immediate ingress of the 50 outside air through the ducts 5 into the area to be heated, and direct it into immediate contact with the flues or into the area behind the flues to necessitate its passing between and being heated by said flues, I prefer to provide 55 a cover 16, formed to fit over the front of the casing 1, and provided with side panels 17 which close the spaces B between the side walls 2 and the combustion chamber 60 10 and flues 9 to divert the incoming air to between the flues. This cover 16 is also provided with an upper horizontal panel 18, which extends below the top of the casing 1 and slightly above the top of the flues 9 to 65 retard the air flow and heat same; and with

a lower horizontal panel 19, which serves to confine the area about the combustion chamber 10, and is disposed above the bottom to provide and permit free passage of the air. These panels 17, 18 and 19, also 70 serve to support a wire or other mesh 20 of any configuration and are preferably designed to provide an ornate enclosure, which in addition to performing the functions recited, may add to the embellishment of a 75 room.

It will be noted that the air coming in from the outside through the ducts 5, is diverted to the back, over the top of, and around the flues 9, being heated by contact 80 with the heated flues 9 and combustion chamber 10. A portion of this incoming air is drawn into and utilized in the combustion chamber 10. The air thus heated in traveling around and between the flues 9, passes into 85 the room or other area and displaces the colder air therein, the displaced air, which is the lower stratum, being forced and drawn out of the area through the stack 6, which is at the bottom in direct and open communication with the area to be heated. The energy with which the cold air or the used air is forced and drawn out from the closed space is augmented by the hot combustion 90 gases which escaping from the flues 9, enter directly into the stack 6, above the point of communication of same with the closed area. In this wise, the air in a room or other enclosure is continuously displaced, without creating noticeable and objectionable drafts. 95 A moderate, comfortable temperature may be maintained at all times, and the air is always pure and fresh. When heated air is not desired, the stove herein described acts as a ventilator, permitting a continuous 100 inflow of fresh air and an uninterrupted outflow of the used air without the necessity of opening windows or other outlets that develop drafts and induce undesirable air current with the accompaniment of dust and 105 other objectionable matter.

What I claim, is:

1. A device for heating and ventilating a closed chamber comprising a casing having air inlet ducts communicating with the outside air and with said closed chamber, a heating means within said casing and disposed in the path of the air inflowing through said ducts, a stack within said casing and separated from said inlet air ducts, 115 said stack communicating at one end with the outside air and at the bottom being in open communication with said closed chamber, and said heating means having connection with said stack above the inlet thereto 120 at the bottom thereby to utilize the heated products ascending in said stack to educt the used air from said closed chamber.

2. A device for heating and ventilating a closed chamber comprising a casing having 125

- a passageway which communicates at one end with the outside air and at the other end is in open communication with said closed chamber, said casing provided with 5 air inlet ducts separated from said passageway and communicating with the outside air and with the closed chamber, a plurality of heating flues within said casing and communicating with said passageway above the 10 opening thereinto from said closed chamber, said flues disposed in the path of air inflowing through said ducts and means to heat said flues.
3. A device for supplying heated fresh air to, and producing a circulation of the heated air in, and continuously removing the used air from a closed chamber, comprising 15 a casing having a plurality of inlet ducts communicating with the outside air and with said closed chamber, and a central passageway between and separated from said inlet ducts and extending longitudinally therethrough, said passageway being in open communication at the bottom with said closed chamber, a combustion chamber, a plurality of flues connected with said combustion chamber and leading directly into 20 said passageway above the opening thereinto at the bottom to convey into said passageway the products of combustion and set up 25 a draft by which the used air is continuously educted from said chamber through the opening in the bottom of said passageway, said flues disposed in the path of air inflowing through said inlet ducts, and a stack 30 communicating at one end with said passageway and at the other end with the outside air.
4. A device for supplying heated fresh air to, and continuously ventilating, a closed chamber, comprising a casing having inlet ducts communicating with the outside air and with said closed chamber, a partition 35 extending longitudinally through said casing and forming a stack which communicates with the outside air, said partition having an opening in the bottom thereof communicating directly with said closed chamber, a plurality of flues disposed in the path of the inflowing fresh air and suspended from and 40 communicating with said partition, a combustion chamber for heating said flues on the inside, said flues arranged to convey the hot combustion products directly into said stack and create a draft whereby the air in 45 said closed chamber is continuously educted therefrom through said stack together with the combustion products. 55
5. A device for supplying heated fresh air to, and continuously removing the used heated air from, a closed chamber, comprising 60 a casing open at the front and bottom and having inlet ducts communicating with the outside air and with said chamber, a stack fastened to the back of said casing, 65 said stack leading to the outside air and having an opening in the bottom thereof communicating directly with said closed chamber, a plurality of flues connected to and communicating with said stack above the 70 opening therein at the bottom, a combustion chamber connected to said flues to heat same on the inside, said flues arranged to convey the heated gases into said stack and thereby induce a draft whereby the air in said 75 closed chamber is continuously removed therefrom together with the continuously discharging products of combustion. 80
6. A device for heating and continuously ventilating a closed chamber, comprising a casing having inlet ducts for leading into said chamber the outside air, a stack within the casing and separated from said inlet ducts, said stack communicating at one end with the outside air and having an opening 85 in the bottom thereof which communicates directly with the closed chamber, a combustion chamber, a plurality of flues connected with said combustion chamber to heat the air inflowing through said inlet ducts, said flues communicating with said stack above the opening therein at the bottom to convey the products of combustion into said stack and create a draft whereby 90 the used air in said chamber is continuously educted therefrom by and concurrently with the passage of the combustion gases through said stack. 95

In testimony whereof I have set my hand.
CLEVELAND G. TERRY.
